SALAD MIXER

Joseph H. Egy, La Canada, Calif.

Application September 2, 1958, Serial No. 52,467

Term of patent 14 years

(Cl. D44—10)

Fig. 1 is a side elevational view of a salad mixer showing my new design; and

Fig. 2 is an end elevational view thereof.

I claim:

The ornamental design for a salad mixer, substantially as shown.
